UNITED STATES PATENT OFFICE.

CHRISTIAN D. BRENNER AND WILSON D. PRATT, OF CANTON, OHIO.

WATER-HEATER.

1,031,239.

Specification of Letters Patent.

Patented July 2, 1912.

Application filed September 7, 1910. Serial No. 580,883.

To all whom it may concern:

Be it known that we, CHRISTIAN D. BRENNER and WILSON D. PRATT, both citizens of the United States, and both residing at Canton, in the county of Stark and State of Ohio, have jointly invented a new and useful Water-Heater, of which the following is a specification.

Our invention relates to improvements in devices for heating water for the heating of buildings and the like, the invention being applicable either in hot water or steam heating systems, although principally intended for hot water systems.

15 The objects of our invention are to generally improve devices of the character mentioned, to provide a simple, substantial, easily constructed and efficient water heater made up of sections individually formed, 20 preferably by casting, and combined in the manner hereinafter described.

One of the special objects of the invention is to provide a water heater which will be economical in the use of fuel, or in other 25 words capable of utilizing to the fullest extent the heat produced by the combustion of the fuel, while at the same time not being of complicated construction and being very easily cleaned.

30 The objects just noted, together with other objects readily apparent to those skilled in the art we attain by the construction illustrated in the accompanying drawings, although the invention may be embodied in 35 other forms, the construction illustrated being chosen by way of example.

In the drawings Figure 1 is a vertical longitudinal section through a water heater embodying our invention. Fig. 2 is a vertical transverse section on the line 2—2 of Fig. 1. Fig. 3 is a reduced horizontal section on the line 3—3 of Figs. 1 and 2. Fig. 4 is a reduced horizontal section on the line 4—4 of Figs. 1 and 2. Fig. 5 is a reduced 45 perspective view of the main baffle section. Fig. 6 is a perspective view of one of the inter-sectional water connections.

Throughout the several views similar reference numerals indicate similar parts.

50 The numeral 1 indicates a base or ash pit section provided with the front ash removal door 2 and having the grate bars 3 arranged across the top. Upon the base section 1 is arranged the fire box section 4, which section is provided with front and rear double, 55 spaced, perpendicular walls and double, side

spaced walls preferably inwardly slanted at the top as shown in Fig. 2. The space 5 between the walls is adapted to contain water, said space extending entirely around the fire box section except at the fuel door 6 in the front. 60

Upon the fire box section 4 is arranged the baffle duct section 7, which section is provided with double, spaced walls on its four sides as illustrated in Fig. 4, the water space 8 extending entirely around the section. 65

Extending transversely from side to side of said section are a plurality of baffle ducts having internally broad, flat water ways 70 communicating with the water space 8 at both ends of said ducts. The number of baffle ducts will depend upon the required capacity of the heater. In the drawings I have illustrated these baffle ducts as arranged in lower and upper horizontal series, the baffle ducts of the lower series being numbered 9 and the baffle ducts of the upper series being numbered 10. Each of the several ducts is provided with relatively broad, parallel, relatively closely spaced lower and upper side walls 11 and 12 respectively, said side walls being joined along their edges by integral edge walls 13. By this construction the water ways formed by the ducts are made 75 relatively broad and flat in cross section, and the ducts of each series are all disposed with their relatively broad sides inclined to the perpendicular, the ducts of the lower series being illustrated in the drawing as front- 80

wardly inclined at an angle of substantially forty-five degrees and the ducts of the upper series being rearwardly inclined in similar manner and degree. Not only are the two side walls of each duct parallel with 90 each other, but the side walls of all the ducts in each series are also parallel with each other. The lower edge wall of each of the upper ducts is arranged intermediate the upper edge walls of two adjacent lower ducts 100 so that as flames and heated gases arise and pass in an inclined direction upwardly between the lower ducts said flames and gases will be divided when they have reached the upper edges of said lower ducts as will be 105 well understood by an inspection of Fig. 1 of the drawings.

Arranged upon the section 7 is the main baffle section 14 which is provided with spaced walls extending around said section 110 and defining the water space 15, and is also provided with spaced bottom walls extend-

ing entirely from side to side and from front to rear of the heater with the exception of the opening 16^a. The spaced walls of the section 14 define the space 16 opening into the space 15 around all edges, said space 16 being adapted, like the space 15, to contain water, thus providing a layer of water extending substantially across the top of the section 7 from side to side and from front to rear, the lower wall of said space forming the main baffle plate adapted to baffle the flames and gaseous products of combustion, the only means of escape for such products being through the opening 16^a through which opening escape is made into the space 17 and thence upwardly through the flue opening 18 and out through the flue 19. On the section 14 is arranged the section 20, said section constituting the top or uppermost section of the heater. The walls of section 20 are spaced, providing space for water at 21, said space extending entirely over the top of the heater except at the flue opening 18.

25 For the purpose of providing means for more securely holding the sections together the top edge of each section is provided with a groove 22 into which a depending tongue 23 of the next upper section is adapted to enter. Cement may be arranged in the groove 22 when putting the sections together, thus providing tight joints.

Entering the section 4 are the return pipes 24 and leaving the top section 20 are the pipes 25 for conducting the heated water or steam to the radiators or other places where the same is desired. A gage at 26 for determining the pressure may be employed if desired, such gage being of the common well known construction.

40 For the purpose of providing communication between the various sections the walls of such sections are provided with the connecting slots 27 arranged in the outer side walls of the sections adjacent the joints where one section rests upon a lower section. These slots are so arranged that connection between the section 4 and the section 7 is made at one side of the heater, while sections 7 and 14 are connected at the other side of the heater and sections 14 and 20 are connected at the same side as the sections 4 and 7. In this way the water entering the space 5 in the section 4 will be somewhat heated from the fire within said section, the water rising as it is heated in said section and passing into the section 7 at one side of the same, where the water will pass through the space 8, and also back and forth freely through the baffle ducts 9 and 10 from side to side of the section 7, receiving much more heat, whence said water, again rising will pass on the other side of the heater into the section 14, where it will be disposed across the top of section 7 in the spaces 15 and 16,

receiving still further heat, whence it will ascend into section 20 on the first mentioned side again to be heated further in said section 20, whence it is conducted from the heater through the pipes 25 to the place desired. 70

For the purpose of providing communication between the slots 27 of adjacent sections the inner-sectional water connections 28 are provided. These connections are preferably 75 cast of metal and comprise a face plate 29 provided with slots 30 adapted to register with the slots 27 in the adjacent sections and with an inclosing curved wall 31 providing a communicating passage from one slot 30 80 to the other. Through the apertures 32 in the face plate 29 machine screws 32^a extend into the sections to be connected, the face plate 29 being thus drawn up tightly to said sections, with appropriate packing if desired, between the face plate and the sections, whereby passage ways are made from the slots 27 of the lower section to the slots 27 of the next higher section as illustrated 85 in the drawings. 90

By reference to Fig. 1 it will be seen by noting the arrows shown thereon that the flames and heated gases from the fire in the section 4 as they arise are baffled by the forward inclined lower side walls of the baffle ducts 9 and thrown forward and upward against the rearwardly inclined lower side walls of the upper baffle ducts 10. Passing on upwardly said flames and gases will strike the lower surface of the section 14, 100 following the same to the opening 16^a, ascending therethrough, following along the under surface of the section 20 and escaping through the flue opening 18 into the flue 19. Especial attention is called to section 7 and 105 the structure therein shown. It will be seen that without materially obstructing the draft the flames and heated gases are caused to strike the inclined walls of the ducts 9 and 10 in a manner well calculated to heat 110 the water contained in said ducts. It should be noted that any dust deposited on the upper walls of said ducts will have a tendency to slide from the same downwardly into the fire again, and that there are no corners or 115 recesses to hold any quantity of dust or soot in and adjacent said baffle ducts. 125

For the purpose of cleaning out section 14 the door 33 may be provided through which door a suitable scraper or brush may be inserted to remove any dust or soot from the space 17. If desired a similar clean out door may be arranged in section 7 for the purpose of more thoroughly cleaning the baffle ducts 9 and 10. 120

We claim:

1. In a water heater a baffle duct section provided with double walls defining a water space extending around said section, a lower series of baffle ducts extending from 130

- side to side of said section and an upper series of baffle ducts extending from side to side of said section, each of said ducts in both the lower and upper series provided 5 with relatively broad, parallel, relatively closely spaced lower and upper side walls joined along their edges by integral edge walls, the relatively broad and flat water ways thus formed by said ducts communicating with said water space at both ends 10 of said ducts, all of the side walls of the ducts in each series being parallel with each other, the side walls of said lower series being inclined in one direction and the side walls of the upper series being inclined in 15 the other direction.
2. In a water heater a baffle duct section provided with double walls defining a water space extending around said section, a lower series of baffle ducts extending from side to side of said section and an upper series of baffle ducts extending from side to side of said section, each of said ducts in both the lower and upper series provided 20
- with relatively broad, parallel, relatively closely spaced lower and upper side walls joined along their edges by integral edge walls, the relatively broad and flat water ways thus formed by said ducts communicating with said water space at both ends 25 of said ducts, all of the side walls of the ducts in each series being parallel with each other, the side walls of said lower series being inclined in one direction and the side walls of the upper series being inclined in 30 the other direction, and the lower edges of the ducts in said upper series arranged intermediate the upper edge walls of the ducts 35 of the lower series.

In testimony that we claim the above, we 40 have hereunto subscribed our names in the presence of two witnesses.

CHRISTIAN D. BRENNER.
WILSON D. PRATT.
